UNITED STATES PATENT OFFICE.

EDWARD H. DEWSON, OF NEW YORK, N. Y., ASSIGNOR TO THE WESTINGHOUSE AIR BRAKE COMPANY, OF PITTSBURGH, PENNSYLVANIA, A CORPORATION OF PENNSYLVANIA.

TRIP-VALVE FOR AIR-BRAKES.

1,168,488.

Specification of Letters Patent. Patented Jan. 18, 1916.

Application filed April 6, 1911. Serial No. 319,342.

To all whom it may concern:

Be it known that I, EDWARD E. DEWSON, a citizen of the United States, residing at New York, in the county of New York and State of New York, have invented new and useful Improvements in Trip-Valves for Air-Brakes, of which the following is a specification.

This invention relates to air brakes for railway cars, and more particularly to trip valve devices therefor, adapted to be operated by contact devices along the track to open the train brake pipe and vent air therefrom to cause an application of the automatic brakes when the train runs past a danger signal with which the track contact devices are connected.

In order that the brakes may be set with absolute certainty and full force at such times, it is necessary that the vent valve should be opened and remain fully open for a sufficient period of time to allow a very material and rapid reduction of pressure to take place in the train pipe, and it is also desirable that after this sufficient reduction has occurred, the vent valve should be automatically closed or reset, so that the brakes may be released and the train be ready to start again as soon as the danger is past.

Devices for this purpose have been heretofore designed, as covered in my prior application Serial No. 573,798, filed July 25, 1910, but the object of my present invention is to provide improved means for this purpose, which will operate to positively hold the vent valve open until a certain reduction has been made in the train pipe pressure which shall be sufficient to insure the brakes setting and remaining applied until the train is stopped.

With this object in view my improvement comprises a latch or locking mechanism governed by train pipe pressure and normally in position to prevent the closing of the vent valve after the same has been opened, but adapted to be automatically withdrawn from locking position when the train pipe pressure has diminished to a predetermined point, and then permit the vent valve to close.

Various forms of pneumatic latch or locking mechanism for this purpose may be devised, one of which is illustrated in the accompanying drawing, in which—

Figure 1 is a vertical sectional view of a

trip valve device embodying one form of my improvement; Fig. 2, an end elevation; Fig. 3, a sectional view showing a modified form of trip lever for opening the valve; and, Fig. 4, a fragmentary sectional view showing a slightly modified form of latch mechanism.

As shown in Fig. 1 of the drawing, the pneumatic locking or latch mechanism is applied directly to the stem, 4, of the vent valve, 5, which controls the discharge from the train brake pipe 6, through the exhaust port 7, to the atmosphere.

Any desired or preferred form of trip mechanism may be employed for opening the vent valve by the track contact device, such, for instance, as the plunger 8, having striking head 9, as indicated in Figs. 1 and 2, or operated by a double fulcrumed lever 10, as shown in Fig. 3.

As shown in Fig. 1, the locking mechanism comprises the latch member 13, connected to the movable abutment or piston 11, which is normally held in locking position against the gasket 16, by the train pipe pressure but is adapted to be moved by spring 15, to its release or unlocking position, when the train pipe pressure is at or below a predetermined point, as determined by the tension of spring 15. The latch mechanism 75 80 85 90 95 100 105 110

may be connected up to the vent valve device in any desired manner, so as to hold the valve open after it has been actuated by the trip, but as here shown, the stem 4 is provided with a beveled collar 12, for coöperating with the inclined edge of the latch to allow the same to yield as the stem of the valve is forced upward against its spring 14. Whenever the vent valve is thus opened by the upward thrust of the plunger 8, the beveled collar passes above the latch 13, which immediately moves back to its normal locking position, and prevents the descent of the stem and the closing of the vent valve as long as the train pipe pressure is sufficient to hold the latch piston seated against the tension of spring 15. In this manner the vent valve is held wide open, causing a sudden and very material reduction in train pipe pressure, which insures the rapid and full application of the brakes.

When the train pipe pressure has diminished to a certain low point, the spring 15, acts to move the piston and latch to unlocking position in which the beveled collar 12 110

clears the edge of the latch and the spring 14 then returns the stem and vent to close the train pipe discharge. The mechanism is thus automatically reset to its normal position.

5 5 and the train pipe pressure may then be increased for releasing brakes in readiness for the train to proceed.

As shown in Fig. 1, the latch 13 is rigidly connected with the piston 11, so that the 10 train pipe pressure to which the piston is subjected normally holds the latch in its locking position, and when the stem 4 is thrust upward by the trip mechanism, the beveled collar 12, acting against the latch 15 draws the piston momentarily away from its seat on gasket 16, as the collar passes above the latch. The piston and latch are then instantly forced back to locking position by the air pressure acting on the piston.

20 According to the modification shown in Fig. 4, the latch 13^a is disconnected from the piston 11, so as to allow for an independent movement, and is provided with a light spring 13^b, for normally holding the latch in 25 its locking position against the collar 12 of the valve stem 4. With this construction, the resistance to the upward movement of the stem is greatly reduced as it is not necessary to overcome the air pressure upon piston 30 11, which remains seated against its gasket, and the collar merely moves the latch outward against the light spring 13^b, which then returns the latch to locking position, and prevents the descent of the collar 12, and 35 valve stem 4. When the train pipe pressure has diminished to a certain point, the spring 15 acts to move the piston 11 against the latch and actuates the same to its unlocking or release position, as before described, 40 thereby permitting the closure of the vent valve. As the train pipe pressure is then increased for releasing and recharging the brake system, the piston 11 is again moved outward against its seat, and the spring 13^b 45 acts to reset the latch to its normal position against the beveled collar 12 of the valve stem.

While the vent valve 5 is here illustrated as venting the train pipe directly to the 50 atmosphere it will be obvious that this valve may, if desired, operate as a pilot valve to vary the pressure upon a relay mechanism, which then effects the corresponding opening and closing of the train pipe discharge.

55 It will also be apparent that various changes and modifications as to the form and location of the latch mechanism may be made without departing from the scope of my invention.

60 I claim as my invention and desire to secure by Letters Patent:—

1. A trip valve device for air brakes, comprising a vent valve, trip mechanism for causing the opening of the same to discharge 65 air from the train pipe, and a latch device

governed by train pipe pressure for positively preventing the closure of the valve until the train pipe pressure is reduced a given amount.

2. The combination of a train brake pipe, 70 a vent valve for discharging air therefrom, trip mechanism for opening said valve, and locking means normally subject to the train pipe pressure for controlling the closing of the vent valve. 75

3. A trip valve device for air brakes, comprising a vent valve for discharging air from the train pipe, trip mechanism for causing the opening of said valve, and yielding locking means governed by train 80 pipe pressure for positively holding said valve open until the train pipe pressure is reduced to a predetermined degree.

4. A trip valve device for air brakes, comprising a vent valve for discharging air 85 from the train pipe, trip mechanism for causing the opening of said valve, and a yielding latch device governed by the train pipe pressure for preventing the closure of said valve until the train pipe pressure is reduced to a certain point.

5. A trip valve device for air brakes, comprising a vent valve for controlling the discharge of air from the train pipe, trip mechanism for causing the opening of said 95 valve, a spring for closing said valve, and locking means governed by the train pipe pressure for holding said valve open until the train pipe pressure is reduced a given amount. 100

6. A trip valve device for air brakes, comprising a vent valve for controlling the discharge of air from the train pipe, trip mechanism for effecting the opening of said valve, a latch for holding said valve open 105 and a movable abutment normally subject to train pipe pressure for actuating the latch.

7. A trip valve device for air brakes, comprising a vent valve for controlling the discharge of air from the train pipe, trip mechanism for effecting the opening of said 110 valve, means normally tending to close said valve, a spring and a latch device governed by the opposing pressures of the train pipe 115 and said spring for holding said valve open until the train pipe pressure is reduced a given amount.

8. A trip valve device for air brakes, comprising a vent valve for controlling the discharge of air from the train pipe, trip mechanism for opening said valve, means normally tending to close the train pipe discharge, and latch mechanism normally subject to the train pipe pressure for temporarily holding said train pipe discharge open. 120

9. A trip valve device for air brakes, comprising a vent valve and trip mechanism for opening same, a latch for locking said 125

valve open, and a movable abutment normally subject to the train pipe pressure for releasing the latch.

10. A trip valve device for air brakes, comprising a vent valve and trip mechanism for opening same, a latch for locking said valve open, and a piston subject to train pipe pressure for releasing the latch, said latch having an independent movement

relative to the piston when the valve is opened.

In testimony whereof I have hereunto set my hand.

EDWARD H. DEWSON.
